UNITED STATES PATENT OFFICE

CARL A. MATSON, OF LYNNFIELD, MASSACHUSETTS

METHOD OF SEALING

No Drawing.

Application filed May 14, 1927. Serial No. 191,542.

My present invention relates to the art of sealing, and more particularly to the art of sealing as applied to packaging articles, the covering of which is sealed by adhesive.

Heretofore in packaging articles by enclosing the same in a wrapper of paper, fabric, or the like, or in packaging articles and attaching an encircling band thereto, it has invariably been the custom to apply adhesive to the covering material, while the adhesive was wet, or it has been customary, if the covering material was already coated with a layer of adhesive, to wet or moisten such adhesive material before the same could be utilized. The result has been that the process of packaging by these methods is extremely slow, as it is necessary to hold the covering material in position a sufficient length of time to allow the adhesive to set, otherwise the enclosing material may be pulled apart. Also, it was necessary to keep such packaged articles away from moisture as the moisture attacked the adhesive, with the result that the packaging was destroyed.

In my present invention, I have obviated objections to prior methods of packaging, and the object of my invention, therefore, is an improved method of sealing or packaging.

In carrying out my invention, I utilize an adhesive which is preferably previously applied to the enclosing material for the articles to be packaged, and which adhesive is dry, or nearly so, and which becomes sufficiently soft under the application of heat to adhere strongly to a portion of the covering material to which it is already applied. Such adhesive is softened but momentarily and becomes hard practically instantaneously and is not affected by moisture. This characteristic of the adhesive to set instantaneously on the withdrawal of heat therefrom enables me to substantially speed up the process of packaging and thus to reduce the cost of producing packaged articles.

The adhesive is characterized by the fact that it is in dry, or nearly dry form, the percentage of moisture content being negligible and such adhesive is preferably of a colloidal nature, which, after heating, has practically all trace of its solvent driven away

and is not ordinarily affected by heat. Such adhesive may come in any preferred form, such as thin sheets which may be placed between two opposing surfaces of an enclosing material such as paper or fabric, and the heat and some slight pressure is applied to the enclosing material on either side of the adhesive, which becomes momentarily softened and then immediately sets, and it has been found impossible to separate the layers of enclosing materials from each other. If desired, such adhesive may be applied in liquid form to labels or other enclosing materials and allowed to have its solvent evaporate therefrom. When in this condition, the adhesive is practically dry and the portion of the material, such as the label having the adhesive thereon, is brought over into engagement with a clean portion of the material and pressure applied to both the portion having adhesive thereon and the clean portion, with the result that such two portions are strongly attached together.

The specific ingredients of the improved adhesive are relatively unimportant, as my invention is applicable to any adhesive capable of being softened on the application of heat and pressure. An example of such adhesive is commercial collodion.

Having thus described my invention, what I claim as new is:

1. That improved method of wrapping and sealing which consists in applying a non-hygroscopic adhesive to the enclosing materials of the articles to be wrapped and sealed and applying heat momentarily thereto.
2. That improved method of wrapping and sealing which consists in applying a non-hygroscopic adhesive to the enclosing materials of the articles to be wrapped and sealed and applying momentary heat and pressure thereto simultaneously.
3. That improvement in the art of wrapping and sealing which consists in applying to the enclosing material of the articles to be wrapped and sealed, a non-hygroscopic adhesive in dry form and of a colloidal nature capable of being softened on the momentary application of heat, applying momentarily

to the adhesive both heat and pressure whereby the adhesive becomes instantly set.

4. That improvement in the art of wrapping and sealing which consists in applying to the enclosing material of the articles to be wrapped and sealed, a liquid non-hygrosopic adhesive of a collodial nature capable of being softened on the momentary application of heat, allowing the same to dry, and 10 applying momentarily to the adhesive both heat and pressure whereby the adhesive becomes instantly set.

In testimony whereof, I have signed my name to this specification.

CARL A. MATSON.
